J. SIMON

PROCESS OF CHLORIDIZING ROASTING OF BURNT PYRITES

Filed Oct. 27, 1920

Jacob Simon,
INVENTOR

BY ATTORNEYS

Bennie, Davis, Marvin & Edmonde,

UNITED STATES PATENT OFFICE.

JACOB SIMON, OF FRANKFORT-ON-THE-MAIN, GERMANY, ASSIGNOR TO THE FIRM BEER, SONDHEIMER & CO., OF FRANKFORT-ON-THE-MAIN, GERMANY.

PROCESS OF CHLORIDIZING ROASTING OF BURNT PYRITES.

Application filed October 27, 1920. Serial No. 420,062.

To all whom it may concern:

Be it known that I, JACOB SIMON, a citizen of Germany, residing at and whose post-office address is Frankfort-on-the-Main, 5 Germany, have invented certain new and useful Improvements in Processes of Chloridizing Roasting of Burnt Pyrites (for which I filed an application in Germany, August 2, 1917), of which the following is 10 a specification.

The chloridizing roasting of burnt pyrites and the like was formerly carried out in furnaces, of the non-muffled type, in which the material was raked. Later, rotary chloridizing furnaces, like the Herreshoff furnace, came into use. The Eamen, Beskow and Wedge furnaces were of the rotary type and were of suitable construction for chloridizing roasting. Buddens roasted in a 15 kind of shaft furnace without addition of carbon; his process necessitating continual renewal of the parts of the furnace.

By the present invention the chloridizing roasting is performed, with the addition of 20 from 0 to 2 per cent of coke breeze or coke dust, by blowing air under pressure into a furnace which resembles a rotary grate producer, but which is particularly adapted for the purposes of the invention.

Pyrites have been roasted in a furnace 25 which is similar to the known high pressure gas producer, but such a roasting is an oxidation process, altogether different from the chloridizing roasting with which this invention is concerned. This process of chloridizing roasting of burnt pyrites is conducted, according to the present invention, 30 by roasting, on the counter-current principle and in a stationary shaft closed air-tight, the material mixed with salt and with from 0 to 2 per cent of coke breeze, by means of air under pressure passing upwards, the 35 completely roasted material being removed mechanically. This procedure has the particular advantage that it is continuous and essentially more uniform than the processes of chloridizing roasting hitherto known. This has the further result that there is a 40 large yield of soluble copper with a small consumption of salt. Moreover, the continuous process requires considerably less power than the known processes need.

A suitable furnace for the process is shown in the accompanying drawing. It

consists primarily of a stationary air-tight 55 shaft. The material (for instance, burnt pyrites mixed with salt and with from 0 to 2 per cent of powdered coke) is charged through the hopper *e* and leaves the furnace at *d*, while the air passes through the 60 furnace in the opposite direction. The gases escape through the lateral pipe *f*. The air blast enters at *a* and is distributed, as is apparent from the drawing, over the annular 65 peripheral grate and the centre grate. The grates are of the stepped form, but the grate plates are inclined at an angle of nearly 45°.

The roasting zone proper is from 10-20 70 cm. above the point of the grate so that the latter is not burnt. The rising air cools the roasted material, roasts the material in the roasting zone and pre-heats the material above this zone.

The roasted material falls into the rotating gutter *b*, is removed therefrom by the 75 scraper *c* and is discharged through the valved hopper *d*. The control of the air blast and of the speed of rotation of the 80 gutter, as well as the adjustment of the scraper (the furnace is always full) keep the roasting zone at the correct level. A number of poking holes are provided in the 85 side of the shaft whereby bridging of the material may be prevented.

I claim:

1. In the chloridizing roasting of burnt pyrites and the like, the improvement which comprises progressively passing the charge of material to be chloridized downwardly 90 en-masse through an air-tight stationary shaft, passing a current of air upwardly through the column of charge in a direction opposite to the direction of movement of the charge, and discharging the roasted material at the bottom of the shaft.

2. In the chloridizing roasting of burnt pyrites and the like, the improvement which comprises progressively passing the charge including the material to be chloridized 100 mixed with salt and with carbonaceous material in amount not exceeding about 2% en-masse through an air-tight stationary shaft, and passing a current of air through the column of charge in a direction opposite to the direction of movement of the charge.

3. In the chloridizing roasting of burnt

pyrites and the like, the improvement which comprises progressively passing the charge including the material to be chloridized mixed with salt and with coke breeze in amount not exceeding about 2% downwardly en-masse through an air-tight stationary shaft, passing a current of air under pressure upwardly through the charge, and mechanically removing the roasted charge from near the bottom of the shaft. ¹⁰ In testimony whereof I have affixed my signature in presence of two witnesses.

JACOB SIMON.

Witnesses:

HARRY KATZENSTEIN,
MAXWEIN.
